ELECTRIC VIBRATOR

Otto Hermann, St. Louis, Mo.

Application May 20, 1937, Serial No. 143,664

3 Claims. (Cl. 200—90)

This invention relates to electric vibrators of the type that will convert unidirectional current into alternating current.

An object of the invention is to provide a vibrator of this type embodying a step-up or step-down transformer that will convert the unidirectional current into alternating current resembling in character a sine wave curve, and which will also turn back such alternating current into unidirectional current, as desired.

The invention comprises the vibrator and the parts and elements thereof combined and arranged in the manner illustrated in the drawings and hereinafter described.

Other objects and advantages of the invention will be apparent from the following description, reference being made to the annexed drawings, in which—

Fig. 1 is an elevation of my improved vibrator.
20 Fig. 2 is a sectional view on the line 2—2 of Fig. 1.

Fig. 3 is a sectional view on the line 3—3 of Fig. 1.

Fig. 4 is a sectional view on the line 4—4 of 25 Fig. 1.

Fig. 5 is an elevation of an assembly embodying the invention with all of the electric circuit connections.

Fig. 6 is a view illustrating the current input 30 part of the vibrator.

Fig. 7 is a similar view illustrating the current output part of the vibrator.

Fig. 8 is a vertical sectional view of the insulators, certain of the bushings being in section 35 to disclose the attaching rod.

In the embodiment of the invention shown, the contacts 1 and 2 are the interrupter contacts, constituting an automatic circuit breaker, and are electrically connected to the terminals of the 40 coil 3 of the electro-magnet 4. The contact 1 is attached to the spring 5, which is connected by the conductor 6 to one of the leads of the coil 3 (Fig. 6). The spring 5 is attached to an armature 20 secured to the supporting member 7 of 45 "Bakelite" or the like, which is mounted for oscillation so as to move the contact 1 into and out of engagement with the contact 2. The member 7 also supports on one side the contact members e and on the opposite side the contact 50 members e', all of which contact members are connected with the metallic lugs 8 (Figs. 3 and 6). The contact member 2 is attached to a stationary supporting member 9 of "Bakelite" or the like and is electrically connected to the conductor 10. A conductor 11 is connected to the

other lead of the coil 3. Beyond the opposite side of the movable supporting member 7 from the stationary supporting member 9, a stationary supporting member 12 of "Bakelite" or the like is mounted. The supporting member 9 has attached thereto a pair of contact members a and another pair of contact members d (Fig. 2), and the supporting member 12 has attached thereto a pair of contact members b and another pair of contact members c (Fig. 4). Metallic lugs 13 10 are attached to the respective contact members a, d, b and c (Figs. 2 and 4).

While the "Bakelite" supports shown are circular, it is obvious that they may be of different shapes and that the contacts may be arranged 15 thereon otherwise than as shown. As illustrated (Figs. 2, 3 and 4), the contacts are circular and are spaced approximately 90° from each other, forming annular series of contacts.

As shown in Figs. 5 and 6, the contacts a and 20 c are connected to the positive terminal of a battery B by the conductor 10, and the contacts b and d are connected by the conductor 11 with the opposite or negative side of the battery B. Rods 14 are attached to stationary end members 25 15 and 16 and extend through holes in the stationary supports 9 and 12, and also through the vibrating support 7 which is located between said supports 9 and 12. These rods have thereon enlarged portions 17' and spacer sleeves or bushings 17 and 18, holding the members 12 and 15 and the members 9 and 12 and the members 9 and 16, respectively, in rigid spaced relationship. The supporting member 7 has holes therein of slightly larger diameter than the diameter of the 35 sleeves 17 so as to permit the member 7 to slide or vibrate freely along said sleeves 17. Nuts 14' screwed on the ends of the rods 14 hold the assembly together in proper aligned relationship.

The oscillating member 7 is supported by 40 springs 19 mounted on the sleeves 17 and seated upon the support 12. A soft iron armature 20 is attached to the oscillating support 7. When the circuit in the coil 3 is closed by engagement of the contact members 1 and 2, the electro-magnet is energized and the armature 20 is attracted and moved thereby in opposition to the springs 19, the compression of which rapidly increases and decreases in step with the closing and opening of the circuit in the coil 3. When 50 the circuit in the coil 3 is opened by disengagement of the contacts 1 and 2, the compression in the springs 19 is reduced to its former condition since said springs expand to move the support 7 to its former position, as shown in 55

Fig. 6. This process is repeated very rapidly, resulting in a vibratory motion of the support 7 so long as the current is allowed to pass through the coil 3 of the armature.

5 Figs. 5 and 6 clearly illustrate the electrical connection of the contacts *a* and *d* and also the contacts *b* and *c* mounted, respectively, on the stationary supports 9 and 12 with the source *B* of unidirectional current. Figs. 5 and 6 also show 10 the electrical connection of the contacts *e* and *e'* on the oscillating support 7 with the primary *P* of a transformer. The contacts *a* and *c* are connected together by the conductor 10, which also leads to the source *B* of unidirectional current at 15 the positive terminal thereof; and the contacts *b* and *d* are connected together by the conductor 11 leading to the negative terminal of the battery *B*. The contacts *e* and *e'* on the vibrating support 7 are connected to the terminals of the primary coil *P* of the transformer by the conductors 20 21 and 22, respectively.

When the vibrator is in operation and the relative positions of the parts with respect to each other are for a moment as indicated in Figs. 5 and 25 6, the current passes from the positive terminal of the battery *B* through the conductor 10 to the contacts *a*, and thence to the contacts *e*, and thence through the conductor 22 through the primary coil *P* of the transformer, and from 30 there through the conductor 21 to the contacts *e* and *d*, from where the current flows to the negative terminal of the battery through the conductor 11. In the following moment, the contacts *e'* engage the contacts *b* and *c* so that the current flow through the primary coil *P* of the transformer is now in a direction opposite from the one indicated by the arrows in Fig. 6.

A further explanation of the function of the vibrator as it effects the direction of current flow 40 in the primary circuit *P* of the transformer is as follows:

At the instant the vibrator is connected to a source of unidirectional current, as shown in Figs. 5 and 6, the current in the primary circuit *P* of the transformer will flow in the direction indicated by the arrows in Fig. 6. At the same time, the armature 20 which is supported by the vibrating support 7 that carries the contacts *e* and *e'* is moved downwardly by the electro-magnet 4. 45 Thereby the electro-magnetic circuit connected in shunt with the conductors 10 and 11 leading to the terminals of the battery *B* will be interrupted at the contacts points 1 and 2. In consequence of this interruption, the contacts *e* and *e'* will now 50 make electrical connection with the contacts *b* and *c*, resulting in a change in the direction of current flow in the primary circuit *P* of the transformer. This is to say that now the current flow in the primary coil of the transformer 55 is in a direction opposite from that indicated by the arrows in Fig. 6. At this time, the springs 19 quickly move upwardly the support 7, and thereby the contacts *e* and *e'*, into electrical connection with the contacts *a* and *d*. This upward 60 and downward movement of the supporting member 7 is effected very rapidly, and in step therewith a reversal in the direction of current flow in the primary *P* of the transformer is the

inevitable result. At the instant the contacts *e* and *e'* connect with the contacts *a* and *d*, the current passes through the primary coil *P* in one direction and, at the subsequent movement, the contacts *e* and *e'* connect with the contacts *b* and *c*, with the result that the current passes through the primary coil *P* in the opposite direction. Therefore, the current flowing through the primary of the transformer is an alternating current having characteristics similar to a sine wave 10 curve.

On the left-hand side of Fig. 5, and specifically in Fig. 7, is shown the rectifier section of the vibrator. In these views of the drawings, the connection of the secondary *S* of the transformer 15 to the contacts *e* and *e'* on the vibrating member 7 by the conductors 23 and 24, respectively, is shown. These views of the drawings also show the conductor 25 connected to the contacts *a* and *c* on the stationary supporting members 9 and 12 20 and the conductor 26 connected to the contacts *b* and *d* on the same stationary members. From the conductors 25 and 26, as determined by the nature of the vibrator, only unidirectional current is obtained so that one of the conductors is 25 positive and the other negative.

The invention may be varied otherwise than as specifically indicated herein without departure from the nature and principle thereof.

I claim:

1. A vibrator comprising, in combination, an interrupter to effect a vibratory motion, and two stationary members, each of which carries four contacts, and a contact and armature carrying vibratory member interposed between the stationary members without any interference to oscillation, the contacts of the stationary members and the contacts of the vibratory member being positioned around a circle on opposite ends of the diameter, and each of the contacts carried 40 by the two stationary members facing a contact united with the vibratory member.

2. A vibrator comprising an interrupter to effect a vibratory motion of a contact and armature carrying vibratory member interposed between two contact carrying stationary members for free oscillation, the contacts projecting on either side of the vibratory member and the contacts projecting only on one side of the stationary members, all of said contact members being 50 positioned around a circle on opposite ends of diameters to provide an aligned relationship between the contacts of the stationary members and the contacts of the vibratory member, as specified.

3. A vibrator comprising, in combination, a disc-like contact and armature carrying vibratory member interposed between two disc-like contact carrying stationary members, means to hold said stationary members in rigid spaced relationship with respect to the vibratory member, and interrupter mechanism including coiled springs placed between stationary member and vibratory member to effect a rapid oscillatory motion of the vibratory member between two 65 fixed positions, as specified.

OTTO HERMANN.
